UNITED STATES PATENT OFFICE

2,534,153

AXIAL CYLINDER PUMP ESPECIALLY
INTENDED FOR MOVING LIQUIDS

Leo Widmer, Feldbach-Zurich, Switzerland, assignor to Schweizerische Lokomotiv- und Maschinenfabrik, Winterthur, Switzerland

Application May 1, 1946, Serial No. 666,308
In Switzerland March 11, 1946

3 Claims. (Cl. 103—37)

1

My present invention relates to improvements in liquid pumps of the expansible chamber type, comprising multiple annularly disposed cylinders with reciprocating pistons.

In pumps of this class it is known to operate the pistons by means of an oblique or skew disc which is given a rotating motion by the drive shaft, and to vary the pump output by changing the inclination of the said disc. Such regulating, however, requires that the adjusting movement be transmitted to the rotating shaft of the pump and, further, the adjustable pivoted regulator parts mounted on the said shaft are engaged by the full torque of the pump shaft.

Also it is known in the art to so operate axial pistons with adjustable stroke, by means of a rotating cam disc, that the pistons contact the cam for a longer or shorter period of time by virtue of axially displacing the cam disc and thus correspondingly perform a greater or lesser stroke of the pistons. The piston heads, which abut against the cam disc for a certain length of time only, thus are subjected to heavy impacts when being contacted by the cam, except when being set for full stroke. The piston heads and the cam thus are subjected to a very pronounced wear and tear and even may fail in operation.

In the design of an axial-piston engine according to the present invention, the adjustment of the inclination of the skew disc and the impactwise operation of the pistons is avoided by combining the piston drive, operated by means of an axially adjustable skew disc which always is positively engaged by the pistons, with a control regulating the beginning of the working stroke proper by having the pistons close off an opening in the cylinder walls. The said combination of piston drive and working-stroke control is of such character that an axial displacement of the skew disc relative to the cylinder-wall openings gives rise to a change of the piston course utilizable for pumping purposes.

One embodiment of the present invention is illustrated in the drawing, in which:

Fig. 1 shows a longitudinal section of a pump with horizontal axis of rotation,

Fig. 2 a similar section of a modified disposition of the drive gear in a pump with vertical axis of rotation,

Fig. 3 a partial cross-section on the line III—III of Fig. 1, and

Fig. 4 a partial longitudinal section of a modification of Fig. 1 comprising auxiliary suction stand-pipes.

An inner casing 4 and the cylinder block 5 are mounted inside the outer pump case 1 which is closed off by the covers 2 and 3. Bores 7, twelve in number, are provided in the said block 5, in

2

which the pistons 8 operate. The latter are brought to bear against the skew disc 10 by means of the springs 9 and contact same along generating lines of the conically tapered piston heads 11. Lateral apertures 13 are provided in the bores 7 and provide communication between the latter and the jacket space 1a. The latter is filled with liquid up to a level 22 approximately. The ends of the cylinder bores are closed off by spring-loaded balls 14 from the delivery chamber 28, which balls act as check valves.

The skew disc 10, by means of the ball bearings 16 and 17, is rotatably mounted, in an inclined position relative to the drive shaft 18, on the catch plate 19 non-rotatably secured to the drive shaft 18. The latter is mounted in the inner casing 4 and the cylinder block 5 on the ball bearings 20 and 21. The catch plate or driver 19 is bearing against the adjusting socket or thimble 25 through the intermediary of the thrust ball bearing 23. The said socket 25 is a sliding fit in the inner casting 4 and is rotated therein when axially displaced on the threads 24. The adjusting socket 25 is axially displaced by the worm wheel 27 journaled in the inner casing 4 and engaging the worm rim 26.

When the drive shaft 18 is rotating, the pistons 8 reciprocate axially. During each working cycle (to-and-fro motion) of the pistons, the apertures 13 are unmasked once so that the liquid to be pumped may pass therethrough from the jacket space 1a into the cylinder bores 7. After an aperture 13 is again masked by a piston 8, the liquid trapped in the respective bore 7 is shot through the check valve 14 into the delivery chamber 28 and out therefrom through the riser 29. The apertures must be so dimensioned that the time during which they are unmasked by the pistons is sufficient to permit of filling the cylinder bore 7 with liquid from the jacket space 1a, which latter e. g. may be under atmospheric pressure.

When the adjusting socket or thimble 25 occupies the axial position according to Fig. 1, that portion of the piston stroke which serves for raising liquid is identical with the distance S, i. e. with the overlap of the butt face 12 of the piston 8 relative to the edge 15 of the aperture 13. When the thimble 25 then is withdrawn or displaced to the left, the said overlap and thus the useful piston stroke S and the pump output is less. When the thimble 25 is displaced so far to the left that the piston butt-face 12 at the end of the piston stroke only extends up to the edge 15, the pump output is zero (no-load), and the liquid, in spite of the pistons 8 operating with full stroke, is sucked through the ports 13 into the cylinder bores 7 only to be discharged therethrough again, i. e. no pressure is being

built up in the bores 7 and the valves 14 remain closed.

The design according to Fig. 2, only showing the adjusting-socket portion of the pump, but in vertical disposition, differs from that of Fig. 1 in that the socket 30 axially guided in the inner casing 4 is not adjustable by means of threads, but is displaced by a spring 31 abutting with its top end against the stationary casing-cover 32. The degree of compression of the spring 31 is defined by the total pressure of the pistons 8 subjected to the pressure of the delivered liquid. When the pressure to be overcome by the pistons 8 is high, the spring 31 is more compressed and the output thus automatically decreased owing to the lesser useful piston travel. The reverse holds true when the pressure to be overcome by the pistons becomes smaller. In this manner, the pump output advantageously may be decreased at a higher pump pressure without loss of power, and increased at a lesser discharge head.

The suction flow into the bores 7 may be improved or accelerated by inserting—as shown in Fig. 4—suction stand-pipes 35 into the cylinder walls, wherein balls 36 serving as check valves are disposed. During a pressure stroke, the said balls are pressed against the restricted apertures 37 of the stand-pipes 35. During a suction stroke, the balls 36 are brought to abut against the perforated steps 38 so that the liquid may flow into the cylinder bores 7. The overflow function of the port 13 remains intact in such a disposition. Such auxiliary suction line is provided for in cases, e. g., when it is desired that the pistons be sucking liquid from the jacket space 1a from the very beginning of the suction stroke, in contrast to the design of Fig. 1 wherein suction is starting only at the moment when the port 13 is unmasked by the piston 8.

What I claim and desire to secure by Letters Patent is:

1. A pump, especially intended for moving liquids, comprising a drive shaft, a cylinder block, a plurality of cylinders in said block arranged in parallel and in a circle concentric with said drive shaft, a piston reciprocable in each cylinder, each cylinder having an inlet port over which the end of the piston slides, an oblique disk of constant slant associated with said pistons in power transmitting relation, a carrier member for said disk mounted for rotation with said drive shaft and for axial movement along said shaft to vary the beginning of the pressure stroke of the pistons by axial movement of said oblique disk relatively to said inlet openings, said disk being rotatably journaled on the carrier member, a stationary casing secured to said cylinder block and surrounding said carrier member and oblique disk, an axially movable sleeve member disposed concentrically with said drive shaft and having a larger diameter than said oblique disk, said sleeve member being guided for axial movement within said casing, and a thrust bearing mounted between said sleeve member and said carrier member for directly transmitting axial thrust from one member to the other.

2. A pump, especially intended for moving liquids, comprising a drive shaft, a cylinder block, a plurality of cylinders in said block arranged in parallel and in a circle concentric with said drive shaft, a piston reciprocable in each cylinder, each cylinder having an inlet port over which the end of the piston slides, an oblique disk of constant slant associated with said pis-

tons in power transmitting relation, a carrier member for said disk mounted for rotation with said drive shaft and for axial movement along said shaft to vary the beginning of the pressure stroke of the pistons by axial movement of said oblique disk relatively to said inlet openings, said disk being rotatably journaled on the carrier member, a stationary casing secured to said cylinder block and surrounding said carrier member and oblique disk, an axially movable sleeve member disposed concentrically with said drive shaft and having a larger diameter than said oblique disk, said sleeve member being guided for axial movement within said casing, a threaded hollow stud on said sleeve member and engaging a complementary thread provided on said casing, a worm drive operatively connected to said sleeve member to rotate the latter and thereby cause axial adjustment thereof, and a thrust bearing disposed between said sleeve member and said carrier member for directly transmitting axial movement from the sleeve member to the carrier member.

3. A pump, especially intended for moving liquids, comprising a drive shaft, a cylinder block, a plurality of cylinders in said block arranged in parallel and in a circle concentric with said drive shaft, a piston reciprocable in each cylinder, each cylinder having an inlet port over which the end of the piston slides, an oblique disk of constant slant associated with said pistons in power transmitting relation, a carrier member for said disk mounted for rotation with said drive shaft and for axial movement along said shaft to vary the beginning of the pressure stroke of the pistons by axial movement of said oblique disk relatively to said inlet openings, said disk being rotatably journaled on the carrier member, a stationary casing secured to said cylinder block and surrounding said carrier member and oblique disk, an axially movable sleeve member disposed concentrically with said drive shaft and having a larger diameter than said oblique disk, said sleeve member being guided for axial movement within said casing, resilient means between said axially movable sleeve member and said stationary casing to elastically support the sleeve so that a smaller effective stroke of the pistons will produce a larger delivery pressure and a larger effective stroke a smaller delivery pressure.

Certificate of Correction

Patent No. 2,534,153

December 12, 1950

LEO WIDMER

It is hereby certified that error appears in the above numbered patent requiring correction as follows:

In the heading to the printed specification, line 8, foreign filing date, for "March 11, 1946" read *March 8, 1946*;

and that the said Letters Patent should be read as corrected above, so that the same may conform to the record of the case in the Patent Office.

Signed and sealed this 5th day of June, A. D. 1951.
